UNITED STATES PATENT OFFICE

HAROLD D. GRINNELL, OF PITTSFIELD, MASSACHUSETTS, ASSIGNOR TO THE G. C. A. MANUFACTURING COMPANY, OF PITTSFIELD, MASSACHUSETTS, A CORPORATION OF MASSACHUSETTS

ATTACHMENT FOR LAMP-BULB-REPLACING APPARATUS

Application filed July 13, 1929. Serial No. 377,979.

This invention aims to provide an improved attachment for incandescent lamp bulb replacing apparatus to permit the use of apparatus of this character designed for normal application to lamps mounted in pull-type or slip-connection sockets, on lamps screwed or otherwise detachably mounted in fixed sockets.

The invention will best be understood from a description of a specific useful embodiment thereof illustrated in the accompanying drawings, to which reference may be had.

Referring to the drawings, Figure 1 represents a side view of the device as a whole operatively applied to lamp bulb replacing apparatus of the pull socket type in which the clamping arms are shown in the open position;

Fig. 2, a similar view showing the parts in the closed position and gripping a lamp bulb;

Fig. 3, a detail perspective view of the top of one of the arms;

Fig. 4, a top view of a portion of the holder on the line 4—4 of Fig. 1, showing the method of attachment of the converging ends of the arms;

Fig. 5, a sectional view on the line 5—5 of Fig. 4, and

Fig. 6, a cross section of the bulb and gripping attachment on the line 6—6 of Fig. 2.

Referring to the accompanying drawings, the illustrative form of lamp bulb replacing apparatus herein shown comprises the bowed clamping arms 10, which are pivotally connected together at their lower ends and supported upon an upright portion 11, the upper ends of the arms being free and adapted to be moved into and out of gripping position with a lamp socket (not shown) which is engaged by the arcuate channel members 12, while the middle portions of the arms normally freely enclose the lamp bulb. Thus applied, no part of the arms 10 ordinarily

comes into contact with the glass portion of the lamp bulb, which otherwise would be in danger of breakage. To permit the application of the arms 10 directly to the glass portion of the lamp bulb when mounted in a fixed socket without endangering the bulb, I provide an auxiliary attachment which may readily be applied to and removed from the clamping arms. In the present embodiment of my device, I provide a plurality of flexible auxiliary arms 13 constituting suspension members detachably supported at their upper ends on the free ends of the clamping arms 10 and extending downward in converging relation within the structure formed by the clamping arms, the lower ends being curved inward to lie in a plane disposed freely below the lamp bulb 14 and secured together at a common point intermediate the length of the clamping arms and also preferably coincident with the axial line of the upright portion or standard 11.

The auxiliary arms 13 may be of any suitable material adapted to the purpose, these parts in the present embodiment being three in number, corresponding to the number of clamping arms 10, and constructed of metallic strip, as for example phosphor-bronze, adapted to be flexed toward and away from the lamp bulb, the inner ends being secured together by suitable locking means, such as a bolt 15 and preferably also, but not necessarily, by a rigid holder 16 herein shown as a metallic plate underlying the arms 13 and secured thereto by the bolt. To further insure the given position of the arms 13 at their junctions and to maintain them throughout their length in correct position relative to the respective supporting clamping arms 10, I provide on the holder 16 radial extension portions 17 underlying the inner extremities of the auxiliary arms, each of said extension portions having lateral mem- 90

bers 18 adapted to be clamped around one of the auxiliary arms 13.

Means are provided to permit my device to be readily mounted in operative position on the clamping arms, and removed therefrom with equal facility, without necessitating the use of tools or locking the parts together. This I accomplish in the present embodiment by the provision of a hood-like structure 10 on each of the auxiliary arms of which the auxiliary arm itself is an integral part, such structure being adapted to be freely slipped over the top of the corresponding clamping arm. To these ends the upper extremity 15 of the auxiliary arm 13 is curved outward and then downward to form an inverted U-shaped portion 18 which hooks over the top of the clamping arm, the free downwardly extending end thus formed being held 20 against outward displacement by an endless band 19 encircling both the clamping arm 10 and the auxiliary arm 13 and roughly shaped to conform to the contour of the clamping arm, the band 19 and free end of 25 the U-shaped portion 18 being suitably secured together.

Cushioning means, such as a plurality of tubular rubber pads 20 carried on and enclosing each of the auxiliary arms 13 and arranged at appropriate points in its length 30 for engagement with the glass portions of the lamp, are provided to insure a suitable gripping medium and to prevent fracture of the lamp bulb.

It will be observed that my device constitutes a flexible open structure forming a 35 unitary assembly which may be readily mounted on and detached from the main structure without involving interlocking connection therewith, or removal of any of the parts of the main structure. The renewal 40 of the cushioning pads 20 may be easily accomplished by removing the securing means, namely the bolt 15, which holds the arms 13 and holder 16 in fixed relationship.

My invention obviously is not restricted 45 to the particular embodiment herein shown and described.

I claim:

1. In combination with apparatus for 50 gripping a lamp socket and removing the same with or without the lamp bulb mounted therein, auxiliary means for non-locking association with said apparatus for gripping a lamp bulb and removing the same independently of its socket.

2. In a device of the class described, in 55 combination with apparatus having clamping arms for gripping a lamp socket of the push type and removing the lamp bulb with the socket, gripping mechanism constituting a unitary structure, including non-locking securing means, for cooperative association with the clamping arms for engaging and 60 rotating the lamp bulb in either of opposite

directions independently of the lamp socket.

3. In a device of the class described, in combination with apparatus having a group of rigid clamping arms movable toward and away from each other for gripping a lamp 70 socket, a series of flexible arms movably connected together to form an open unitary structure for support on and within said group of clamping arms for receiving and gripping a lamp bulb of the type having a 75 turning connection with its socket, and non-locking securing means.

4. In a device of the class described, in combination with gripping mechanism including a series of clamping arms movable toward and away from each other for gripping a lamp socket, auxiliary gripping means, including a plurality of flexible arms connected together to form a unitary assembly, securing means carried on the flexible arms 80 permitting said supplemental gripping means to be slipped on and off the clamping arms, and cushioning members carried on said flexible arms for engaging the glass portion 85 of a lamp bulb.

5. Lamp bulb removing and replacing mechanism, including a series of resilient arms movable toward and away from each other and connected together to form a unitary structure, said arms being adapted to 90 directly engage a lamp bulb and to rotate the same in either of opposite directions independently of its mounting.

6. Lamp bulb gripping mechanism for cooperative non-locking association with separate mechanism for gripping lamp sockets and removing the same with or without a lamp bulb mounted therein, said lamp bulb gripping mechanism including a series of 100 flexible arms connected to form a unitary structure and adapted to directly engage and rotate a lamp bulb having a turning connection with a rigidly supported socket.

7. Gripping mechanism for directly engaging and turning lamp bulbs in either of opposite directions independently of the lamp socket, said mechanism constituting a unitary structure including non-locking securing means for providing cooperative association 110 between said gripping mechanism and separate apparatus for removing and replacing lamp bulbs with their sockets by application directly to the socket.

8. Lamp bulb removing mechanism, including a plurality of flexible arms movably connected together and forming a unitary assembly adapted to be slipped on and off gripping apparatus having a series of clamping arms at least equal in number to said flexible arms and adapted to support the same, said 120 first mentioned mechanism having cushioning members for directly engaging and rotating a lamp bulb in either of opposite directions independently of the mounting for the lamp bulb.

9. In apparatus for removing and replacing electric light bulbs, a unitary structure comprising a series of flexible arms connected together at one of their ends and having their free ends arranged in diverging relation, securing means including a receiving portion provided on the free end of each of said arms adapted to be slipped over a support, and cushioning means carried by said arms for gripping the lamp bulb.

10 In testimony whereof, I have signed my name to this specification.

HAROLD D. GRINNELL.
